ABSTRACT OF THE DISCLOSURE

Hydrocarbons are recovered from an oil shale formation in situ by injecting an electrolyte into the formation through two or more wells and imposing a potential drop across the formation between the wells to pass electrical current therethrough and heat the same, to a temperature sufficiently high to pyrolyze the hydrocarbons therein, while maintaining sufficient pressure on the formation to prevent vaporization of the electrolyte. The wells may be linked together through the formation by fracturing or directional drilling, or a combination of both.

This invention relates to the hydro-electrolysis of oil shale in situ.

In one aspect, the invention relates to the injection of an electrolyte into an oil shale formation to fracture same, and to application of an electrical current to heat said shale while maintaining pressure on the formation sufficient to prevent vaporization of said electrolyte.

In another aspect, the invention relates to the production of hydrocarbons and non-condensable gases both during and after hydro-electrolysis of oil shale in situ by a sequence of operations comprising electrocarbonization and hydro-electrolysis.

In another aspect, the invention relates to varying the pressure required to prevent vaporization of the electrolyte in inverse relation to the ratio of the weight of salt to the weight of water when an aqueous salt is used as the electrolyte.

In another aspect, the invention relates to the production of hydrocarbons and non-condensable gases from oil shale by injecting an aqueous electrolyte into the formation through two or more wells, and impressing a voltage between two of said wells to heat the formation, while maintaining sufficient pressure on said formation to prevent vaporization of said electrolyte, and producing gas and/or oil through one or more other wells. Alternatively, the products can also be removed from the formation via the wells impressed with the voltage.

In U.S. Patent 3,137,347, pyrolysis of oil shale in situ by means of electrocarbonization was disclosed. The cost of electrical power was recognized to be "a major item" in the operation of the process, but no solution was advanced. It is an object of this invention to reduce the power needed to pyrolyze oil shale in situ. Another object of the invention is to produce hydrocarbons and non-condensable gases from oil shale at lower temperatures than were heretofore possible.

Other aspects, objects and the several advantages of the invention will be apparent to one skilled in the art upon studying the drawing, specification, and appended claims.

In accordance with the invention, a method is provided for producing hydrocarbons such as oil and non-condensable gases from oil shale in situ by injecting an electrolyte into the oil shale, and applying electrical current to heat the shale while maintaining pressure sufficient to prevent vaporization of the electrolyte.

Suitable electrolytes include aqueous salts such as salts of the alkali metals, or mixtures of such salts. Representative examples of these salts include sodium chloride,

2

sodium sulfate, sodium carbonate, and so on. It will be apparent to one skilled in the art that the addition of various electrolytes to water is a variable which can be controlled. A high electrolyte content in the water would raise the boiling point of the water and thus reduce the pressure necessary to pyrolyze the shale.

The technique of hydro-electrolysis can be applied after electrocarbonization has been started in the manner described in U.S. Patent 3,137,347 or hydro-electrolysis can be used from the beginning. In one specific embodiment, two wells are drilled at a distance from one another in the oil shale formation, an electrolyte such as an aqueous salt is injected therethrough, an electrical potential is impressed across the casings of said wells to heat the shale formation, and sufficient pressure is maintained on the formation to prevent vaporization of the electrolyte. The wells may be linked together by either fracturing or directional drilling, or by a combination of the two. By the latter method, directional drilling need not be relied upon to directly hit another well. Regardless of the method used to link the wells, the electrolyte is injected into the formation under sufficient pressure to fracture the shale between the wells, and the pressure is maintained so as to prevent vaporization of the electrolyte.

After the heating zone has been established in the shale, it can be extended indefinitely by drilling additional wells into the shale, injecting electrolyte into the formation under sufficient pressure to fracture same, and applying electrical current to heat the shale while maintaining a pressure sufficient to prevent vaporization of the electrolyte. Said additional wells can be directionally drilled so that a greater spacing would result.

The hydrocarbons and non-condensable gases produced by the process of this invention can be recovered by drilling one or more producing wells between the wells impressed with electrical current. These wells must also be pressured to prevent vaporization of the electrolyte.

Referring now to the drawings:

A multi-well system is illustrated in combination with means for practicing one embodiment of the invention.

Well bores 1 and 2 hold casings 3 and 4 through which a suitable electrolyte such as brine is delivered to formation 11 by means of pumps 8. Pressure sufficient to fracture the formation is supplied by pumps 8. A source of electrical current 6 is used to heat the formation, while pressure means 7 maintain sufficient pressure on the formation to prevent vaporization of the electrolyte. Oil and non-condensable gases can be recovered from formation 11 via production well 5 which is cased.

An electrical connection is made between the casing of the two wells 3 and 4 with the electrical circuit being completed through the brine in the fractures connecting the two wells in the oil shale zone. The casing is cemented to the well bore face near the oil shale zone in a conventional manner. A high voltage A.C. or D.C. potential of 440 volts or higher applies potential between the two wells to heat the formation with sufficient back pressure of up to 1530 p.s.i.g. maintained on the wells so that temperatures of between 500° F. and 600° F. are maintained in the brine in the fractures 9 and 10. In this manner, the formation between the two wells is heated and the shale pyrolyzed at moderate temperatures below 750° F. Heating in this manner is continued for several months prior to production of the produced oil through cased production well 5. Production well 5 is produced by flowing or by a pump not shown. Oil and gas can be produced during the heating period.

Brine which may be saturated can be injected into casings 3 and 4 during the heating process. It is preferred that a saturated solution of brine be used as this will allow better conduction of current and thus more heating of the formation. The following concentrations of brine in

water for different salts can be used depending upon the temperature of the water.

	Percent
Sodium chloride	39
Calcium chloride	60
Potassium chloride	50
Sodium sulfate	40
Sodium carbonate	40

The amount of salt which can be dissolved in the water is a function of the temperature of the solution, and the water can be heated prior to injection in order to as nearly as possible saturate the water with the particular salt being used. The invention is not limited to the use of any particular salt, but sodium chloride is preferred since it is readily available in ground waters.

It will be apparent to one skilled in the art that it is possible to make fuel gas from the coke remaining on the shale after it has been retorted by injecting air and/or steam into the spent shale. Removal of coke by air and/or steam will also prevent current flow through the spent shale.

In the practice of the invention, low temperatures are maintained by introducing increments of electrolyte into the formation while maintaining sufficient pressure to keep the temperature at the desired level. For example, to pyrolyze at 600° F., it is necessary to maintain a pressure of 1530 p.s.i.g. If the shale locally becomes hotter than 600° F., the water will boil and the steam will transfer heat to cooler portions of the formation.

In principle, the concept of the invention is to raise the temperature of the shale sufficiently high to pyrolyze the hydrocarbons therein, while maintaining sufficient pressure on the formation to prevent vaporization of the electrolyte.

Reasonable modification and variation are possible within the spirit and scope of the invention, the essence of which is producing hydrocarbons and non-condensable gases from oil shale in situ by injecting an electrolyte into the shale and applying electrical current thereto while maintaining pressure sufficient to prevent vaporization of the electrolyte.

I claim:

1. A method for producing hydrocarbons from oil shale formations in situ penetrated by at least two wells which comprises fracturing said formation to increase the overall flow permeability between said wells through said formation, introducing an aqueous electrolyte into said formation to increase the electrical conductivity of said formation, imposing a potential drop across said formation to promote current flow therethrough and consequent heating thereof and maintaining sufficient pressure on said formation to retain an aqueous electrolyte conductive phase within said formation.
2. A method in accordance with claim 1 wherein said electrolyte is a mixture of water and an inorganic salt.
3. A method according to claim 2 wherein said inorganic salt is an alkali metal salt.
4. A method according to claim 1 wherein said electrolyte is injected into said oil shale using gas pressure to fracture said oil shale and to maintain said pressure sufficient to prevent vaporization of said electrolyte.
5. The method of claim 1 wherein the amount of said aqueous electrolyte injected is sufficient to produce a substantially continuous conductive path through said formation between said wells.
6. The method of claim 1 wherein the said potential drop is sufficient to substantially elevate the temperature of said formation and increase the mobility of said hydrocarbons.
7. The method of claim 6 wherein said temperature is elevated by an amount of up to about 600° F.
